UNITED STATES PATENT OFFICE.

FRANCIS E. SCHENKER, OF WALLINGFORD, CONNECTICUT, ASSIGNOR TO THE DOWD-ROGERS CO. INC., OF WALLINGFORD, CONNECTICUT, A CORPORATION OF CONNECTICUT.

DESIGN FOR A PERCOLATOR.

Application filed November 10, 1928. Serial No. 28,825. Term of patent 7 years.

To all whom it may concern:

Be it known that I, FRANCIS E. SCHENKER, a citizen of the United States, residing at Wallingford, in the county of New Haven and State of Connecticut, have invented a new, original, and ornamental Design for Percolator, of which the following is a specification, reference being had to the ac-

companying drawing, forming part thereof.

The figure is a perspective view of the article showing my new design.

I claim:

The ornamental design for a percolator as shown.

FRANCIS E. SCHENKER.
